2 Claims. (Cl. 196—67)

1

This invention relates to a process and apparatus for the cracking or partial or complete combustion of fuels and the generation of power.

The removal or separation of valuable products such as benzene, toluene and other liquid or gaseous hydrocarbons and other gases from cracking products is very expensive owing to the plant which has to be provided and the power and heat required.

To burn or crack oils such as gas oil, boiler oils, tars, pitches and the like, it has hitherto been essential to atomise or spray the oil or the like using steam or air at elevated pressure and in some cases with pre-heating and filtering of the oil or the like.

Furthermore, by direct combustion of the oil and the like, a comparatively large excess of air is required for complete combustion, for example an excess of 60% above the theoretical, thus increasing the losses in the waste gases and decreasing the combustion temperature. Furthermore, in most cases the oil cannot be used advantageously in internal combustion engines.

It is an object of the present invention to provide a process and apparatus to overcome these disadvantages, and at the same time to obtain valuable hydrocarbon products.

According to the present invention a process is provided wherein fuel is partially or completely burnt in a burner, whereupon tar or oil or powdered pitch or powdered coal or hydrocarbon gases or a mixture thereof is mixed with the combustion gases, the sensible heat of the combustion gases being sufficiently high to crack the oil or tar or powdered pitch or powdered coal or hydrocarbon gases, whereafter the cracking products are cooled in one or more heat exchangers, and if they are not already under a sufficient degree of pressure are compressed to a degree sufficient to cause condensation of a part of the cracking products or combustion products and the remainder thereof is passed through one or more of the aforesaid heat exchangers to increase the temperature thereof. The gases are then passed through one or more gas turbines.

Examples of hydrocarbon gases which may be cracked in the process are natural gas and coke oven gas.

Preferably the fuel employed for providing the heat is a small proportion of the oil or tar or powdered pitch or powdered coal or hydrocarbon gases to be cracked, and once the process has been started a small proportion, for example 5 to 10% of the gas produced may be re-cycled and used as the fuel for producing the heat required

10

using air or steam as the motive power for re-cycling.

If desired the process of the invention may be operated under pressure, and catalysts may be employed.

Both the primary and secondary air and also the fuels used in the process may, if desired, be pre-heated.

The cracking in the burner may be effected in stages by introducing the oil or the like at a plurality of points and if desired different kinds of oil or powdered pitch or powdered coal or tar or hydrocarbon gases may be introduced at these different points.

15

The invention also includes an apparatus for carrying out the process of the invention comprising a burner having inlets for fuel and air for combustion at one end, a conduit for introducing oil or tar or powdered pitch or powdered coal or hydrocarbon gases into the combustion products, an outlet conduit for removing the cracking products, a compressor for compressing the air or the cracking products and one or more heat exchangers for heat exchange between the aforesaid gases.

20

The invention further includes a burner comprising a chamber, an inlet for fuel and air for combustion at one end, one or more inlets for injecting the oil, tar, or powdered pitch or powdered coal or hydrocarbon gases, a conduit containing an injector, said conduit connecting the fuel inlet and the chamber at a point beyond the first inlet for oil, tar, or powdered coal or powdered pitch or hydrocarbon gases, and an outlet for the products produced.

25

Preferably also the burner contains one or more inlets for secondary air.

30

It should be understood that the term "air" as used herein includes other oxygen-containing gases and also oxygen with or without the addition of steam or carbon dioxide.

35

In the burner, tar or oil or gas may be partially burnt for the generation of producer gas, water gas and combustion gases or mixtures of these gases. The sensible heat of these gases and undecomposed steam or carbon dioxide is used for the cracking of the oils, tars and gases. The air or oxygen-containing gases or oxygen and steam or carbon dioxide required for the reaction may be used pre-heated or superheated. The gases thus obtained may be used directly for the heating of furnaces, boilers or the like or after cooling and removal of some components, for power generation.

40

This modification may also be used advanta-

2

geously for the production of synthesis gases in connection with the synthetic production of oil such as by the Fischer-Tropsch and similar synthesis and hydrogenation processes. In this case oxygen is used for the process.

Some embodiments of the invention will now be described by way of example with reference to the accompanying drawings, in which Figs. 1 to 11 show diagrammatically eleven embodiments of apparatus for carrying into effect the processes of the invention.

Referring to Fig. 1 of the drawings, hydrocarbon gas or oil is supplied to the burner 1 through conduit 2 controlled by valve 2a under increased pressure and oxygen or air or oxygen-enriched air is supplied to the burner through conduit 3 controlled by valve 3a, whilst steam and/or carbon dioxide also under pressure is similarly supplied through conduit 4 controlled by valve 4a. Hydrocarbon-containing gases are passed through conduit 5 controlled by valve 5a through the heat exchanger 6 where they are heated and then passed through conduit 7 controlled by valve 7a into the burner 1, in which they are cracked by the hot combustion products. The hot combustion products containing the cracked hydrocarbon gases leave the burner 1 through conduit 8 controlled by valve 8a and pass through heat exchanger 9, in which they are cooled, and thence by conduit 10 controlled by valve 10a to heat exchanger 11, in which they are further cooled and thence through conduit 12 controlled by valve 12a into the cooler and precipitator 13, in which easily liquefied gases and vapours are condensed, and leave via conduit 14 controlled by valve 14a. The uncondensed gases are then heated by passing through heat exchanger 11, through conduit 15 controlled by valve 15a, thence passing to the gas turbine 16 from which they pass via conduit 17 controlled by valve 17a through heat exchanger 9 to the gas turbine 18, from which they leave by conduit 19 controlled by valve 19a, passing through the boiler or heat exchanger 20 and thence to the consumer at atmospheric or increased pressure, as desired.

Referring to Fig. 2 of the drawings, oil and/or tar and/or hydrocarbon gases is admitted into burner 21 through conduit 22 controlled by valve 22a and air and/or oxygen is introduced via conduit 23 controlled by valve 23a, whilst steam and/or carbon dioxide is introduced through conduit 24 controlled by valve 24a. The oil and/or tar and/or gas is burnt in the burner and oil and/or hydrocarbon gases for cracking is admitted through conduits 25 and 26 controlled respectively by valves 25a and 26a. The products of combustion carrying the cracking products leave through conduit 27 controlled by valve 27a, and pass through heat exchanger 28 and conduit 29 controlled by valve 29a to heat exchanger 30, and thence via conduit 31 controlled by valve 31a to compressor 31b where they are compressed and then passed to cooler and precipitator 32, in which vapours and easily liquefied gases are condensed and are removed through conduit 33 controlled by valve 33a. The uncondensed gases leave through conduit 34 controlled by valve 34a and pass through the activated carbon plant 35, and thence via conduit 36 controlled by valve 36a to the compressor 37, and thence through the further activated carbon plants 38 and conduit 39 controlled by valve 39a through heat exchanger 30 to the gas turbine 40, the gases leaving the turbine 40 via conduit 41 controlled by valve 41a,

and passing through the heat exchanger 28 to the gas turbine 42 from which the gases leave via conduit 43 controlled by valve 43a, part being sent to the consumer and another part passing via conduit 44 controlled by valve 44a through boiler or heat exchanger 45, a part of the gas being then re-cycled to the conduits 39 and 41 (as shown) by conduits 46 and 47 controlled respectively by valves 46a and 47a, further parts of the gas being re-cycled to the burner 21 via conduit 48 controlled by valve 48a and to the conduit 22 via conduit 49 controlled by valve 49a.

Referring now to Figure 3 of the drawings, air is admitted through conduit 50 controlled by valve 50a to the compressor 51 which it leaves under pressure through conduit 52 controlled by valve 52a, oil and/or gases being injected therein through conduit 53 controlled by valve 53a. The mixture then passes into the burner 54 in which it is burnt, and oil and/or hydrocarbon gases admitted through conduits 55 and 56 controlled respectively by valves 55a and 56a is cracked by the combustion products. The combustion and cracking products leave via conduit 57 controlled by valve 57a and pass through the heat exchanger 58 and conduit 59 controlled by valve 59a to the heat exchanger 60, and thence via conduit 61 controlled by valve 61a to the cooler and precipitator 62 in which liquid hydrocarbons and easily liquefied gases and vapours are precipitated and are removed via conduit 63 controlled by valve 63a, a part of the uncondensed gases being also removed via conduit 64 controlled by valve 64a, the remainder passing through conduit 65 controlled by valve 65a through heat exchanger 60 to the gas turbine 66, the gases leaving which pass through conduit 67 controlled by valve 67a through the heat exchanger 58 to the gas turbine 68, from which the gases leave via conduit 69 controlled by valve 69a and pass to the consumer with the required pressure.

Referring to Fig. 4 of the drawings, air is introduced through conduit 86 controlled by valve 86a into the compressor 87 from which the air leaves under pressure via conduit 88 controlled by valve 88a, and passes through heat exchanger 89 to the gas turbine 90, whence it passes via conduit 91 controlled by valve 91a through heat exchanger 92 into the gas turbine 93, whence the air leaves, still under pressure, through conduit 94 controlled by valve 94a, a part of the air then being passed via conduit 95 controlled by valve 95a into which oil and/or tar is admitted through conduit 96 controlled by valve 96a, the mixture being burnt in the burner 97, oil and/or tar being introduced through conduit 98 controlled by valve 98a into the combustion products in which the oil and/or tar is cracked, the mixture of combustion and cracking products leaving via conduit 99 controlled by valve 99a, thence passing through heat exchanger 92 and conduit 100 controlled by valve 100a to the heat exchanger 89, and thence via conduit 101 controlled by valve 101a to the cooler and precipitator 102 in which tar is condensed and removed through conduit 103 controlled by valve 103a, the gas leaving the cooler and precipitator through conduit 104 controlled by valve 104a, part of the gas then passing through conduit 105 controlled by valve 105a into the internal combustion engine 106, which is fed by the remainder of the compressed air from conduit 94 via conduit 107 controlled by valve 107a passing through the cooler 108 before reaching the internal combustion engine. The exhaust gases from the internal combustion engine leave

via conduit 108 controlled by valve 108a and pass through the boiler or heat exchanger 110 and are used for power generation. The remainder of the gases from conduit 104 proceed via conduit 111 controlled by valve 111a and are recycled to conduits 88 and 91 as shown, via conduits 112 and 113 controlled respectively by valves 112a and 113a for combustion.

Referring to Fig. 6 of the drawings, air is admitted through conduit 114 controlled by valve 114a into the compressor 115, from which it leaves under pressure through conduit 116 controlled by valve 116a. Oil and/or tar is admitted through conduit 117 controlled by valve 117a and the mixture is burnt in the burner 118, into which oil and/or tar is admitted through conduit 119 controlled by valve 119a, the oil and/or tar being cracked by the sensible heat of the combustion products. The mixture of combustion products and cracking products leaves via conduit 120 controlled by valve 120a and proceeds through heat exchanger 121 via conduit 122 controlled by valve 122a through heat exchanger 123 and thence via conduit 124 controlled by valve 124a to the cooler and precipitator 125, in which liquid hydrocarbons and easily liquefied gases are condensed and removed through conduit 126 controlled by valve 126a. The uncondensed gases leave via conduit 127 controlled by valve 127a in which the gases split into two streams, one part going via conduit 128 controlled by valve 128a to the combustion chamber 129 and the other part via conduit 130 controlled by valve 130a to the combustion chamber 131, air for the combustion in the combustion chamber 129 being supplied from the compressor 115 via conduit 132 controlled by valve 132a, the air being pre-heated in the heat exchanger 123. The combustion products leaving the combustion chamber 129 contain excess oxygen and proceed under pressure through conduit 133 controlled by valve 133a through the gas turbine 134 and conduit 135 controlled by valve 135a through the heat exchanger 121 to the combustion chamber 131, in which further combustion takes place. The combustion gases leave the combustion chamber via conduit 136 controlled by valve 136a, passing through the gas turbine 137 and thence by the conduit 138 controlled by valve 138a, and may be used for pre-heating or steam raising.

Referring to Fig. 6 of the drawings, which illustrates a burner according to the invention, air is supplied through conduit 139 controlled by valve 139a to the blower 140 which supplies air under pressure through conduit 141 controlled by valve 141a to the burner 142, fuel being supplied through conduit 143 controlled by valve 143a. Oil and/or powdered coal is introduced through conduit 144 controlled by valve 144a into the combustion gases which crack the oil or coal and the mixture of combustion gases and cracking products leave via conduit 145 controlled by valve 145a, part of the gases are re-cycled via conduit 143b controlled by valve 143c to the conduit 143 and the remainder of the gases is burnt in a boiler 146 by means of air supplied under pressure through conduit 147 controlled by valve 147a. The waste gases which leave the boiler through conduit 148 controlled by valve 148a may be used for pre-heating air or the like.

Referring to Fig. 7 of the drawings, air is admitted via conduit 149 controlled by valve 149a into the compressor 150, from which it leaves under pressure via conduit 151 controlled by valve 151a passing through the heat exchanger 152 into

the gas turbine 153, from which it leaves via conduit 154 controlled by valve 154a, passing through heat exchanger 155 into the gas turbine 156. Part of the air, still under pressure, leaves the turbine through conduit 157 controlled by valve 157a, oil and/or tar and/or powdered coal being injected therein through conduit 158 controlled by valve 158a, and the mixture is burnt in the burner 159. Oil and/or tar and/or powdered coal is introduced through conduit 160 controlled by valve 160a and is cracked by the sensible heat of the combustion products. The mixture of combustion products and cracking products leaves via conduit 161 controlled by valve 161a, proceeding through heat exchanger 155, conduit 162 controlled by valve 162a, heat exchanger 152 and conduit 163 controlled by valve 163a to the cooler and precipitator 168 in which liquid hydrocarbons are condensed and removed through conduit 169 controlled by valve 169a. The uncondensed gases leave via conduit 170 controlled by valve 170a and proceed to the boiler 164, in which they are burnt by means of air supplied under pressure through conduit 165 controlled by valve 165a; a further part of the air under pressure being supplied to the consumer via conduit 166 controlled by valve 166a. The waste gases leave the boiler via conduit 167 controlled by valve 167a and can be used for heating purposes, or allowed to escape through the chimney stack of the boiler.

Referring to Fig. 8 of the drawings, a hydrocarbon gas such as methane, natural gas, coke oven gas, a residual gas from a Fischer-Tropsch or similar synthesis process or from a hydrogenation process is introduced (if it contains hydrogen sulphide) through conduit 171 controlled by valve 171a into the purification chamber 172 for the removal of hydrogen sulphide. The purified gas then passes through conduit 173 controlled by valve 173a into the compressor 174 from which the gas leaves under pressure through conduit 175 controlled by valve 175a, a part passing into the burner 176 in which it is burnt by oxygen admitted through conduit 177a and steam admitted through conduit 178 controlled by valve 178a. If desired the gas passing through conduit 175 may be pre-heated before entering the burner (by means not shown). The remainder of the gas passes through conduit 179 controlled by valve 179a into the combustion products, which have sufficient sensible heat to crack the gases. The mixture of cracking and combustion products leaves via conduit 180 controlled by valve 180a, passing through the boiler 181 and heat exchanger 182, conduit 183 controlled by valve 183a, heat exchanger 184 and conduit 185 controlled by valve 185a to the carbon dioxide removal plant 186, where the carbon dioxide is liquefied and removed through conduit 195 controlled by valve 195a. Instead of the boiler 181 there may be used one or more regenerators. The uncondensed gases leave via conduit 187 controlled by valve 187a and pass through the heat exchanger 184 into the gas turbine 183, from whence they pass via conduit 189 controlled by valve 189a into the gas turbine 190. If more power is required steam or other gases may be admitted through conduit 187b controlled by valve 187c. The gases leaving the turbine 190 by the conduit 191 controlled by valve 191a pass to the organic sulphur purifying plant 192 (if it is desired to remove any organic sulphur compound present) from whence they are sent to the consumer at the desired temperature and pressure through

conduit 193 controlled by valve 193a, after passing through heat exchanger 194.

Referring to Fig. 9 of the drawings, air is admitted through conduit 204 controlled by valve 204a into the compressor 205, from which the air leaves under pressure through conduit 206 controlled by valve 206a, passing through heat exchanger 207 to the gas turbine 208, whence the air leaves, still under pressure, through conduit 209 controlled by valve 209a, passing through heat exchanger 210 to the gas turbine 211, from which the air leaves, still under pressure, through conduit 212 controlled by valve 212a. Oil and/or tar is admitted through conduit 213 controlled by valve 213a, and the mixture is burnt in the burner 214. The combustion gases leave through conduit 215 controlled by valve 215a, and oil and/or tar is admitted through conduit 216 controlled by valve 216a, and is cracked by the sensible heat of the combustion gases. The mixture of combustion products and cracking products passes through heat exchanger 210 and thence via conduit 217 controlled by valve 217a through heat exchanger 207, through conduit 218 controlled by valve 218a into a cooler and precipitator 219, from which condensed liquid hydrocarbons and easily liquefied gases are removed via conduit 220 controlled by valve 220a. The uncondensed gases leave via conduit 221 controlled by valve 221a and are compressed in the compressor 222. A part of the gases is sent to the consumer under the desired pressure through conduit 223 controlled by valve 223a, the remainder being recycled via conduit 224 controlled by valve 224a to the cooler and precipitator 219 or to other parts of the plant (by means not shown).

Referring to Fig. 10 of the drawings, air is admitted through conduit 225 controlled by valve 225a into a multi-stage compressor 226. Part of the air from the compressor leaves via conduit 227 controlled by valve 227a and is used to burn oil and/or tar and/or hydrocarbon gases admitted through conduit 228 controlled by valve 228a in burner 229. Oil and/or tar is admitted through conduit 230 controlled by valve 230a and is cracked by the sensible heat of the combustion products. The mixture of combustion and cracking products leaves via conduit 231 controlled by valve 231a and proceeds through heat exchanger 232, conduit 233 controlled by valve 233a and heat exchanger 234 to the cooler and precipitator 235, from which liquids and liquefied hydrocarbon gases are removed through conduit 236 controlled by valve 236a. The uncondensed gases then proceed through the active carbon plant 237, through conduit 238 controlled by valve 238a, passing through heat exchanger 234 to the gas turbine 239, from which the gases leave, still under pressure, through conduit 240 controlled by valve 240a, through the heat exchanger 232 to the gas turbine 241, from which the gases leave, still under pressure, through conduit 242 controlled by valve 242a, passing through heat exchanger 243, to the internal combustion engine 244. Air is also supplied under compression from the compressor 226 at the same or different pressure from that obtaining in the conduit 227 through conduit 245 controlled by valve 245a, which supplies air to the internal combustion engine for combustion. If desired, a part of the air may also be sent through conduits 246 and 247 controlled respectively by valves 246a and 247a to the conduits 238 and 240 respectively, in order to burn a part of the gases before they enter the turbines 239 and 241. Furthermore, a

part or the whole of the air may proceed via conduit 248 controlled by valve 248a, through heat exchanger 243 and conduit 249 controlled by valve 249a, to the internal combustion engine 244. The gases leaving the internal combustion engine pass through heat exchanger 250 via exit conduit 251 controlled by valve 251a. A part of gases in the conduit 242 may be re-cycled via conduit 252 controlled by valve 252a, to conduit 228.

Referring now to Fig. 11 of the drawings, air is admitted through conduit 253 controlled by valve 253a, and is cooled in the heat exchanger 254, passing via conduit 255 controlled by valve 255a to a multi-stage compressor 256. The air under pressure leaves via conduit 257 controlled by valve 257a, passing through heat exchanger 258. The air then passes through the throttle valve 259 in which it expands, liquid air or gaseous components thereof under pressure leaving via conduit 260 controlled by valve 260a, and gaseous air passing through conduit 261 controlled by valve 261a through heat exchanger 258 to conduit 262 controlled by valve 262a. This air 25 is then split into two streams, a part being recycled via conduit 263 controlled by valve 263a to conduit 255 and the other part being sent via conduit 264 controlled by valve 264a through heat exchanger 254 to the burner 265. Into the 30 burner there is also admitted oil and/or hydrocarbon gas through conduit 266 controlled by valve 266a, and steam and/or carbon dioxide through conduit 267 controlled by valve 267a. Oil and/or hydrocarbon gas is admitted through 35 conduit 268 controlled by valve 268a into the combustion products in the burner 265 and is cracked by the sensible heat thereof. The mixture of combustion and cracking products leaves via conduit 269 controlled by valve 269a, and 40 proceeds via heat exchanger 270, conduit 271 controlled by valve 271a, through heat exchanger 272 and conduit 273 controlled by valve 273a, to the cooler and precipitator 274, from which condensed hydrocarbons and liquefied hydrocarbon 45 gases are removed via conduit 275 controlled by valve 275a. The uncondensed gases leave the cooler and precipitator through conduit 276 controlled by valve 276a through which a part of the gases is sent to the consumer and the remainder is sent to the conduits 277 and 278, controlled respectively by valves 277a and 278a, for the purposes hereinafter specified. Air is also supplied from conduit 264 through a branch conduit 279 controlled by valve 279a, through heat 55 exchanger 272 to the gas turbine 280, gases being admitted through the aforesaid conduit 278. The gases leaving the turbine 280 proceed via conduit 281 controlled by valve 281a through heat exchanger 270 to the gas turbine 282, further 60 gases for heating being admitted through the aforesaid conduit 277. The gases leaving the turbine 282 proceed via conduit 283 controlled by valve 283a to a heat exchanger or boiler.

In connection with refrigeration processes the 65 gases or media used for refrigeration may be compressed to a higher initial pressure than required and before being used for refrigeration they are used for generation of power in gas turbines by utilising the sensible heat of the gases produced.

In connection with synthesis processes such as Fischer-Tropsch processes, ammonia synthesis processes and hydrogenation or refining processes, gases such as carbon monoxide, hydrogen and nitrogen and mixtures of the same may be

produced in the required purity and concentration.

The entire power and steam and a surplus, if required, may be generated in the way shown above.

The oxygen or other gases required for some of the modifications may also be obtained cheaply by utilising this process.

The term "oil" as used in the appended claims means oil or tar or powdered pitch or powdered coal or hydrocarbon gases or a mixture thereof.

I claim:

1. A continuous process for the cracking of oil and the generation of power which comprises at least partially burning a fuel in a burner to produce combustion gases, mixing oil with said combustion gases, the sensible heat of the said combustion gases being sufficiently high to crack the oil, passing the mixture of cracking products and combustion gases through two heat exchangers in series to cool said mixture, passing said cooled mixture through a cooler to remove tar, heavy hydrocarbons and steam, passing the uncondensed residue through a compressor to cause condensation of further constituents of the mixture and raise the pressure, heating the compressed mixture by passing it through one of said heat exchangers, passing the heated mixture still under pressure through a gas turbine, heating the exit gases from said turbine by passing them through the other of said heat exchangers and passing the heated gases still under pressure through a second gas turbine.

2. A cracking apparatus comprising a burner having inlets for fuel and air for combustion at one end, a conduit for introducing oil into the combustion products in said burner, an outlet

5 for removing the mixture of cracking products and combustion gases from said burner, two heat exchangers connected in series to said outlet, a cooler, a conduit connecting the outlet of the second of said heat exchangers to the cooler, a compressor, a conduit connecting said cooler to said compressor, two gas turbines in series, a conduit connecting said turbines and a conduit connecting said compressor and the inlet of the first of said turbines, said last two conduits each forming a part of one of said heat exchangers.

MICHAEL STEINSCHLAEGER.
